UNITED STATES PATENT OFFICE.

WILLIAM W. DEAN, OF CHICAGO, ILLINOIS, ASSIGNOR, BY MESNE ASSIGNMENTS, TO BENJAMIN ELECTRIC MANUFACTURING COMPANY, OF CHICAGO, ILLINOIS, A CORPORATION OF ILLINOIS.

SWITCH.

1,257,463.

Specification of Letters Patent. Patented Feb. 26, 1913.

Application filed June 2, 1913. Serial No. 771,181.

To all whom it may concern:

Be it known that I, WILLIAM W. DEAN, a citizen of the United States, residing at Chicago, in the county of Cook and State of Illinois, have invented new and useful Improvements in Switches, of which the following is a full, clear, concise, and exact description, reference being had to the accompanying drawing, forming a part of

10 this specification.

The present invention relates generally to electric switches of the pressure-operated type, and more particularly to switches of this class which can be positively operated 15 without the exercise of especial care or attention on the part of the user.

Such switches are especially applicable to situations where the time and attention of the user are taken up with other matters 20 and a minimum only can be given to the operation of the switch. An example of such a situation is the operation of the control switch of an electric horn of an automobile. They are also desirable in situations where 25 for any reason the operating pressure cannot be carefully applied.

An object of the invention is to provide a simple and efficient arrangement of parts while maintaining all the advantages of 30 ready and positive operation required by switches of this class. This and other features of my invention will be more fully understood upon reference to the following detailed description taken in connection with 35 the accompanying drawing, and the scope of the invention will be particularly pointed out in the appended claims.

In my co-pending application Serial No. 749,135 I have placed the claims to subject- 40 matter common to said application and this application, and in my co-pending application Serial No. 772,402 I have placed the claims for subject-matter common to said application and this application but not 45 found in application Serial No. 749,135, leaving in this application only claims for subject-matter not disclosed in either of said applications Serial No. 749,135 or Serial No. 772,402.

50 In the drawing, Figure 1 is a general perspective view of a portion of an automobile, illustrating one application of my invention, an application in which the switch embodying the invention controls the circuit 55 of an electric horn;

Fig. 2 is a vertical section of an electric switch constructed in accordance with my invention, illustrating the manner of attaching the same to the spoke of an automobile steering wheel, the section being taken on a 60 plane indicated by the line 2-2 of Fig. 3;

Fig. 3 is a horizontal section of the same taken on a plane indicated by the line 3-3 of Fig. 2;

Fig. 4 is a vertical section, similar to Fig. 65 2, of a modified form of the invention, the plane of section being indicated by the line 4-4 of Fig. 5;

Fig. 5 is a horizontal section, similar to Fig. 3, of such modified form, the plane of 70 section being indicated by the line 5-5 of Fig. 4, and

Fig. 6 is a vertical section, similar to Fig. 2, illustrating a modified contact arrangement.

Throughout these views like characters refer to like parts.

Referring to the drawing in detail and more particularly for the present to the form of the invention illustrated in Figs. 2 and 3, 80 10 designates a cup pressed out of brass or similar material and provided with an exterior thread near its upper edge. An annular ring 11 is provided with an interior thread and is screwed on to the cup 10. A 85 diaphragm 12 covers the cup 10 and is held in place by the ring 11, and upper and lower annular washers 13 and 14 insulate the diaphragm 12 from the cup 10 and ring 11. The cup 10 is composed of material having 90 a substantial thickness so that it is comparatively rigid, while the diaphragm 12 is composed of relatively thin material and is flexible. The cup 10 and diaphragm 12 thus provide a water-proof and dust-proof casting, having one flexible wall. The diaphragm 12, it will be understood, may be composed of any desired metal, such as brass or steel, or of some insulating material. In the latter event, the washers 13 and 14 which would be composed of insulating material where used with a metal diaphragm, may be composed of any desired material, whether insulating in character or not.

One switch contact, designated 15, is secured to the center of the diaphragm 12 by having its threaded shank extending through an opening in the diaphragm into threaded engagement with the contact-actuating member or button 16. As illustrated, 105 110

the contact 15 is provided at the lower end of its threaded shank with a shoulder which bears against the under side of the diaphragm 12, and the button 16 is provided with a central projecting portion which terminates in a bearing face which rests upon the top of the diaphragm 12. The construction is such that the contact 15 may be bodily moved downward in a vertical or central direction by a vertical pressure applied at the middle of the button 16 and it may have its lower end moved laterally by a pressure applied near the periphery of the button whereby the button is responsive to central or peripheral pressure, and while I have described the pressure as being peripheral it will be understood that this term includes any pressure applied off center of the button to tilt the button in any direction. 10 The movements of the contact 15 may also be resultants of both lateral and bodily downward movements. Its exact movement in any given case will depend upon the point and direction of application of the pressure 15 to the button. The periphery of the button extends beyond the ring 11 and is consequently of such size that it may be readily engaged for operation. When pressed near its edge its downward movement is limited 20 by its engagement with the ring 11.

The cooperating contact 18 in the present instance consists of a strip or band of conducting material bent up at its center and secured at its ends to a block of insulation 25 19, which preferably completely fills the bottom of the cup 10 and is secured in place by screws 20 and 21. The contact 18 may be secured to the block 19 in any suitable way, as by screws 22 and 23. The lower end of 30 the contact 15 is pointed and this point extends into an opening 24 formed in the contact 18. This relation of contacts might be termed a pin and socket relation. The pin, however, does not normally engage the walls 35 of the socket. It will be seen that if the contact 15 is pushed bodily downward it will engage contact 18 throughout the periphery of the opening 24. On the other hand, if the pressure upon the button 16 be off center, 40 the contact 15 will be rocked laterally into engagement with a portion of the periphery of this opening. It will also be seen that pressure upon the button 16 at different peripheral points will cause an engagement 45 between different points of the contacts 15 and 18.

Contact 15 is provided with a binding post 25, which is mounted upon the insulating base 19. A short wire 26 connects this post with the contact 15, connection with the latter being provided by the screw 27 threaded into a suitable opening in contact 15. Contact 18 is provided with an upturned end 28 which is slotted at 29 for the reception of the end of the conductor which may

be soldered, or otherwise secured, thereto. The conductors 30 and 31 which connect respectively with the binding post 25 and the terminal 28 are led through a gland in the side of the cup 10. A tubular extension 32 70 is formed on one side of the casing 10 and is exteriorly threaded for the reception of a packing nut 33, which when screwed into position forces the packing 34 into close engagement with the insulating covering of 75 the conductors 30 and 31 and thereby prevents access of water or dust to the interior of the casing.

The casing obviously may be secured to its support in any suitable way, depending 80 largely upon the circumstances under which it is to be used. In the present instance, it is secured to the spoke 35 of an automobile steering wheel, and a strap or band 36 extending around the spoke and secured to the 85 casing 10 is employed for this purpose. In this instance, the same screws, 20 and 21, which hold the insulating base 19 and the casing 10 together, pass through the ends of the strap 36 and perform the additional 90 function of securing the switch to the steering wheel spoke.

In the form of the invention illustrated in Figs. 4 and 5, the case is formed by a base 40 of fiber, or other insulating material, 95 and an inverted cup 41 of thin brass or other material which will provide a top 42 of sufficient flexibility. The button 43 and the upper contact 44 are secured to the center of the diaphragmatic top 42 so as to 100 be capable of the same relative movements as in the case of the corresponding parts in the first form of the invention. The lower contact 45 is similar to the contact 18 but is not provided with an upturned terminal like 105 the terminal 28 of the first form. In this instance the upper contact 44 is connected by a wire 46 with a binding screw 47 in the same way as the corresponding parts are connected in the first form of the invention. 110 In the second form, however, the conductors 48 and 49 are provided with metal tips 50 and 51 which are inserted into adjacent openings in the base 40, the former being directly beneath the screw 47 and the latter 115 directly beneath one end of the contact 45. When screw 47 is screwed down into position, its end engages the end of the tip 50 and securely holds it and the associated conductor 48 in place, and at the same time 120 makes electrical connection between the two. Similarly, a screw 52 extends down through one end of contact 45 and a portion of the base 40 into mechanical and electrical engagement with the tip 51. The base 40 and 125 inverted cup 41 may be secured together in any suitable way, as by the screws 53.

From the description of the operation of the first form of the invention, the operation of the second form will be apparent, 130

the parts in the one bearing the same functional relation as the corresponding parts in the other.

In Fig. 6 I have illustrated contacts 15' and 18' which differ somewhat from the corresponding contacts 15 and 18 of the first form of the invention. They are, however, secured in position and operated in the same way. Contact 15' is provided with a cylindrical or flat head instead of a conical or pointed one, as is contact 15. Contact 18' differs from contact 18 in having the additional strip 60 and a slightly larger opening 24' for the passage of contact 15'. The strip 60 unites opposite portions of the contact and preferably bears upon the base 19, as shown. It is also preferably provided with a central contact point or seat 61, which may be composed of platinum, the same material as the strip, or otherwise, as desired. The circuit may be closed between contacts 15' and 18' either by contact 15' engaging contact point 61 alone or by contact 15' engaging the walls of the opening 24' alone, or by contact 15' engaging both contact point 61 and the walls of the opening 24'. These different closures may be brought about by different manipulations of the pressure-operated member.

In the illustrated application of the invention, namely, that involving the control of the circuit of an electrical automobile horn, which is illustrated in Fig. 1, 54 designates the automobile, 55 the electric horn, 56 the steering wheel, 57 the electric switch, and 58 the conductors extending from the switch to the horn and the electric battery, magneto, or other source of power.

In all the above-described forms of this switch the casing is sealed, that is, remains permanently closed to the entrance of dirt and moisture during the operation of the switch to open and close the circuit as well as when the parts are at rest.

It will, of course, be understood that the invention herein disclosed may be applied to a great variety of uses and that alterations and modifications may be made in the forms herein illustrated without departing from the spirit and scope of my invention. I therefore aim to cover by the terms of the appended claims all such uses, alterations and modifications as properly come within their scope.

Having thus described my invention, what I claim as new and desire to secure by Letters Patent is—

1. An electric switch comprising a sealed casing, coöperating switch contacts within said casing, a pressure operated member outside of said casing having a tilttable and rectilinear movement for operating said contacts.

2. An electric switch comprising a permanently closed casing having a portion of

its wall movable relative to the rest of said casing, coöperating switch contacts within said casing, a pressure operated member outside of said casing secured to said movable portion of the casing wall, and having a tilttable and rectilinear movement for operating the contacts.

3. An electric switch comprising a sealed casing, coöperating switch contacts within said casing, and a tilttable pressure-operated member outside of said casing for operating said contacts.

4. An electric switch comprising a permanently closed casing having a portion of its inclosing wall movable relative to the rest of said casing, coöperating switch contacts within said casing, and a tilttable pressure-operated member operating outside of said casing and secured to said movable portion of the casing wall for operating said contacts.

5. An electric switch comprising a casing having a diaphragmatic wall, coöperating switch contacts in said casing having different relative movements for making and breaking electrical connection in response to different movements of said diaphragmatic wall, and a pressure-operated member outside of said casing for giving the different movements to said wall.

6. An electric switch comprising a casing having a diaphragmatic wall, coöperating switch contacts in said casing relatively movable into and out of electrical engagement at different points in response to different movements of said diaphragmatic wall, and a pressure-operated member outside of said casing for giving the different movements to said wall.

7. An electric switch comprising a casing having a diaphragmatic wall, coöperating switch contacts in said casing, one of said contacts being secured to said diaphragmatic wall, said contacts also having a pin and socket relation, a portion of one extending within an opening in the other, and a pressure-operated member secured to an intermediate portion of the outside of said diaphragmatic wall for actuating the latter to relatively move said contacts into and out of electrical engagement.

8. An electric switch comprising a casing, a pressure-operated member variously movable relative to said casing, and coöperating switch contacts within said casing relatively movable into and out of electrical engagement at different points in response to the different movements of said pressure-operated member, said contacts bearing a pin and socket relation, a portion of one extending within a portion of the other.

9. An electric switch comprising a support, a switch contact mounted on said support, a flexible diaphragm mounted above said support, a switch contact mounted upon

and centrally located of said diaphragm and a tiltable pressure-operated member mounted on said diaphragm and supported thereon at a central point only.

- 5 10. An electric switch comprising a suitable support, a switch contact mounted on said support, a diaphragm mounted above said support, a tiltable pressure-operated member having a central projection engaging said diaphragm and a switch contact mounted on the opposite side of said diaphragm extending through said diaphragm and engaging in said projection in the pressure operated member.
- 10 15. An electric switch comprising a support, a switch contact mounted on said sup-

port, a diaphragm mounted above said support, an operating member centrally engaging said diaphragm, a switch contact on the opposite side of said diaphragm, said switch contact being operatively moved into engagement with the opposite contact by tilting said operating member or by bodily moving the same.

In witness whereof, I have hereunto subscribed my name in the presence of two witnesses.

WILLIAM W. DEAN.
